[57] CLAIM

The ornamental design for a control panel for a combined vehicular radio receiver and cassette player, as shown and described.

DESCRIPTION

FIG. 1 is a top, front and left side perspective view of a control panel for a combined vehicular radio receiver and cassette player showing our new design;

FIG. 2 is a front elevational view thereof; and

FIG. 3 is a right side elevational view thereof. The broken line showing is for illustrative purposes only and forms no part of the claimed design.
